METHOD OF INSTALLING FAUCET
 Alfred M. Moen, 151 Lakeview Drive, R.D. 1,
 Grafton, Ohio
 Filed Feb. 3, 1960, Ser. No. 6,468
 7 Claims. (Cl. 29—157)

This invention relates to a method of installing a faucet. In the particular form here shown it relates to the method of installing a mixing faucet, such as a shower faucet, but the invention is not limited to that particular association. It has for one object to provide a method by which a faucet assembly can be readily installed in a building as rooms are finished.

Other objects will appear from time to time throughout the specification and claims.

The invention is illustrated more or less diagrammatically in the accompanying drawings wherein:

FIG. 1 is an exploded view with parts in section and parts in elevation illustrating the faucet housing, the plaster ground, the escutcheon and the handle members in line and separated from each other;

FIG. 2 is a front plan view of the faucet housing;

FIG. 3 is a transverse section taken on a reduced scale at line 3—3 of FIG. 4;

FIG. 4 is a section taken on an enlarged scale at line 4—4 of FIG. 2;

FIG. 5 is an elevation of the escutcheon;

FIG. 6 is a plan view of the handle cup;

FIG. 7 is an end view of the stop tube;

FIG. 8 is an inside view of the handle for adjusting the faucet;

FIG. 9 is a view illustrating the handle flange;

FIG. 10 is a section through the handle assembly with parts in elevation;

FIG. 11 is an inside view of the plaster ground member; and

FIG. 12 is a diagrammatic showing with parts in section and with some parts in exploded position illustrating the steps in the assembly of the faucet in an installed, complete tub and shower water supply installation.

Like parts are designated by like characters throughout the specification and drawings.

In the particular form here shown the device includes a housing member which is provided with inlet connections 1 and 2. These are, respectively, for hot and cold water and they lead into a central chamber 3 which is closed at one end as at 4 and is provided with an integral extension 5. The space within the chamber 3 and the member 5 receives a valve part or parts or a valve assembly. None is shown in full since this invention is not limited to a particular valve assembly. Generally the valve assembly will include an operating stem. One form of such a stem is shown at 6 in FIG. 1. From the space within the member 5 an opening or discharge outlet 7 leads to a tub connection 8. Surrounding the chamber within the member 5 is a generally circular passage 9 which is connected to a shower outlet 10.

As shown in FIG. 2 a diverter connection 11 may be connected to the outlet 8 and a diverter valve is positioned within this connection. Means for operating the diverter valve are indicated at 12 in FIG. 2. In one position this member closes the passage to the tub and water is discharged to the shower. In another position this diverter member opens the passage to the tub and water is discharged to the tub. The details of the diverter are not shown as they are well known in the trade today and the invention is not limited to the presence or absence of a diverter. The inlet connections 1 and 2 in the forms shown, and particularly as illustrated in FIG. 4, are in communication, respectively, with inlet openings 13 and 14 through which fluid entering the connections 1 and 2

2

reaches the chamber 3 within which the mixing valve is positioned.

The passage through the member 5 may be slightly enlarged, as at 15, and keyways 16 are cut through the member 5 adjacent its outer end. The key which enters the keyways 16 is indicated in position, as at 17 in FIG. 1.

In the exploded view of FIG. 1 the housing parts, the escutcheon and the handle parts are shown in proper relative position. Interposed between the escutcheon and the wall and the valve assembly and housing is a so-called "plaster ground." This member serves a variety of purposes. For convenience when the faucet assembly of this invention is shipped the parts shown separated in FIG. 1 will preferably be fitted together, as shown in FIG. 12, so that the handle, escutcheon, faucet and assembly occupy the relative positions which they occupy when the device is finally completely installed in a position of use. The plaster ground is interposed between the escutcheon and the remainder of the device and serves as a frame and support for the parts in shipment. When the device is to be installed the parts are separated so that they are taken apart as shown in the exploded view of FIG. 1. The plaster ground is used as a positioning member and as a means for determining the size of the opening when a plaster wall is to be installed. In general the parts are separated, as shown in FIG. 1, for installation. It is assumed that the pipes are in place. The faucet housing is then secured to the supply pipes and the plaster ground is positioned over the member 5 of the housing and remains in place while the plaster is finished and dries. It serves thus as a mold or form for the plaster. When the plaster has dried, the plaster ground is removed and the parts are further assembled.

The plaster ground in the particular form shown comprises a generally flat member 18 which is provided with one or more perforations 19 through it. It has a peripheral flange 20 which is beveled as at 21 on its exterior. It has also a central tubular extension 22 which extends farther away from the member 18 than does the flange 21, as shown particularly in FIG. 1. The length of the tubular extension 22 is equal to the length of the valve stem housing 5. When the plaster ground is assembled about the member 5 the inner end of the tubular portion 22 abuts against the valve housing and the outer surface of the flat portion 18 coincides with the outer surface of the wall 23. A keyway 24 may be provided in the tubular portion and a mating projection 25 may be formed on the housing section 5; thus the plaster ground is positioned accurately in relation to the housing as a whole.

After the plaster has set the plaster ground member is removed and the escutcheon member is secured in place. The escutcheon member is provided with a hollow or conical portion 26 which extends into the space left in the wall after the removal of the plaster ground member. The escutcheon also includes a lateral flange 27 and may carry a packing member 28 of rubber or similar material. The size of the extension 27 is such that it overlies the wall and the packing or sealing member 28 is compressed against the wall when the escutcheon is screwed into place by means of the screws 29 which engage threaded openings 30 in suitable extensions of the housing member.

The valve means, of which only the stem 6 is shown, may be inserted in the housing before the escutcheon is put in place or afterward. Whenever it is inserted the key 17 is inserted in the keyway 16 and holds the valve assembly in place within its housing. Thereafter the stop tube 31 is put in place. It is provided with a keyway 32 into which the portion 17 of the key fits and thus the key

17 is held from displacement. The handle may now be applied.

The handle in the form shown in FIG. 1 comprises a gripping member 33 which has an integral knurled or roughened portion 34 and a pointer 35. It is provided also with an integral tubular or hollow extension 36 and an internal flange-forming member 37. As a means of securing the handle to the valve stem 6 there is provided a handle flange which includes a tubular portion 38 of two diameters and an integral flange 39 which may contact the flange 37 of the handle as shown in FIG. 1. A pair of locating tongues 40 is formed in or punched out of the flange 39 and they fit into depressions 41 formed in the flange 37 of the handle. The tubular portion 38 is provided with a flattened or partially arculate member 42.

Cooperating with the handle flange is a handle cup shown in FIG. 6. It includes a flangelike portion 43 and a central tubular portion 44 which terminates in an inwardly directed flange 45. The tubular portion 44 may have a bead 46 to make a tight fit when the handle cup is pressed into place in the handle. The handle may conveniently be formed of plastic.

When the handle is assembled on the valve stem the flat portion 42 fits over a corresponding flattened portion 47 of the valve stem 6. The handle is secured to the valve stem 6 by a screw 48 which engages a threaded opening 49 in the valve stem 6. A finishing plate 50 is provided with spring fingers 51 and may be snapped or sprung into the open outwardly facing depression 52 of the handle 33.

The handle 35 is preferably provided with stops 53 and 53a which engage the keyway or stop 32 on the sleeve 31 and thus limit rotation of the handle in clockwise and counterclockwise direction.

FIG. 10 is a section through the assembly with parts in elevation and showing a modified form. In the modification of FIG. 10 the handle member 33 is the same as that shown in the other figures and described below. The arrangement of the handle parts which engage the valve stem is modified to permit flusher fitting of the handle within the escutcheon so that it does not extend so far out. As shown therefore in FIG. 10, the valve stem 6 extends directly through the flange 37 of the handle. A mounting flange 54, which is provided with engaging tongues 55 and a central tubular portion 56, is secured to the handle by the tongues 55 and is provided with a flat portion and engages the corresponding flat portion of the valve stem 6 in the same manner as that described above in connection with the form of the handle shown in FIG. 1. A second flange 57 is provided and engages the opposite face of the flange 37 of the handle. It is integral with a tubular section 58 which surrounds and is in contact with the tubular section 56. The member 58 terminates in an inturned flange 59 within which an opening is left through which a screw 60 may pass. The screw 60 engages the threaded opening 49 in the valve stem 6 and when it is tightened the parts of the handle assembly are drawn together and secured together as shown in FIG. 10.

Although an operative form of the device has been shown, the invention is not limited to the particular details shown. Many changes may be made in the form, shape and arrangement of parts without departing from the spirit of the invention. In particular, the method of installation might be accomplished with faucet devices of other descriptions and with water supply installations of a variety of types.

In FIG. 12 there are shown the steps in the assembly of a faucet in connection with a complete water supply system including shower and tub outlets or faucets. A diverter is illustrated in the system of FIG. 12. As shown in FIG. 12, 61 comprises a pipe or supply of water to the shower; 62 an elbow; 63 is the shower nozzle support and 64 is a shower head or nozzle. 65

is a water pipe leading to the tub spout. 66 is an elbow. 67 is a tub connection and 68 is a tub nozzle or spout. 69 is a diverter control member. 70 is a head or push button of the diverter control and 71 is a disposable protective cup or cap member for use in covering and protecting the stop tube 31 and the stem 6 and associated parts during plastering.

The use and operation of the device shown, and particularly the method of assembly, are as follows:

Initially a water supply pipe system is installed in or on a wall, but preferably in a wall. The precise details of the water supply system vary in accordance with the fixtures to which it is to be attached. If there is merely a shower connection the supply system will have one arrangement. If there is merely a tub connection the supply system will be different from that for a shower and if, as shown in FIG. 12, there are to be both shower and tub connections, the system of water supply may be that shown in FIG. 12 with a diverter or control member included so that at the will of the user the water may be caused to flow either through the nozzle into the tub or through the shower nozzle or head from above. Although the method of installation is not limited to a particular type of diverter, nor in fact to the presence of any diverter at all, where a diverter is to be included, as in the form of FIG. 12, it may be one which is provided with a spring control biased to hold the diverter in the position for discharge of water into the tub. Where this is the case if the user desires to accomplish discharge of water through the shower, the diverter is moved by pressing upon the member 70 and overcoming the resistance of the spring. The diverter valve is thus carried to the position in which it closes the passages to the tub faucet 68 and opens the passage to the shower nozzle 64. Once this movement has been accomplished the pressure of the fluid moving through the system to the shower will hold the diverter in the shower-directing position. When the water is finally turned off the spring which is biased to move the diverter to the tub discharge position may act and in doing so will turn the diverter to the tub discharge position where it will remain until positively actuated by the user to produce the shower discharge effect. The operation and the details of the diverter form no essential part of the present invention and the method of installation may be accomplished in connection with the total assembly whether or not there is any diverter involved.

As stated above, the water supply system is installed and it will include a housing member such as that shown in section in FIG. 4 and in elevation in other figures. This is connected to the water supply system in the manner shown, for example, in FIG. 12. The details of the supporting means for supporting the water supply pipes and the discharge pipes are not shown as they form no essential part of the invention.

When the water supply pipe system is in position and the housing member is in position and properly connected to the water supply system the faucet might be assembled but generally it will not be until the plastering or comparable finish of the wall has been accomplished. Sometimes, of course, the wall 23, as shown in FIGS. 1 and 12, will be finished with tile or any other suitable finish. Whatever the finish to be applied to the wall may be it is convenient and generally preferable to put the valve stem 6 and associated parts in position within the housing. The stop tube 31 is mounted in position as shown in FIGS. 1 and 12 and the member 18 is moved into or retained in the position shown in FIG. 12. The part 18 is referred to herein as a "plaster ground" and it serves the purpose of a mold about which plastering may take place and which, when removed after the plastering has hardened, will leave a space sufficient to assemble the faucet parts partially flush against the wall and partially within the space. The member 18 is thus in reality a molding part and when the parts are in the position of FIG. 12 plastering and other wall finishing may occur.

After plastering or other wall finishing has been completed the plaster ground 18 is removed. It is shown as partially removed in the exploded position of FIG. 1. During the plastering the covering cup or cap 71 will normally be fitted over the tube 31. This cup or cap 71 may be made of cardboard or other disposable material and it prevents plaster from falling upon the stem 6 and any associated part, so that upon its removal after the completion of the plastering the valve and stem parts are clean and free from any plaster or other material which would interfere with their operation or interfere with the subsequent assembly of the necessary parts.

If we assume that plastering and wall finishing are complete when the parts are in the position of FIG. 12, the next step is to remove the plaster ground member 18 and the cap 71. The plaster ground member may be held in place during plastering and drying by screws that pass through the smaller openings shown in FIG. 11 and are engaged in the threaded openings 30 of the housing member. They are removed, the cap 71 is removed and the plaster ground 18 is removed. The parts 18 and 71 are normally discarded. When they have been removed complete assembly of the faucet can take place. The escutcheon plate 26 is then moved into position over the stop tube 31. It will be noticed in FIG. 5 that there is a notch in the central opening of the escutcheon plate and this notch is fitted over and engaged with the keyway 32 in the tube 31. Screws 29 are then passed through the appropriate openings in the escutcheon plate and engage the threaded openings 30 in the housing. The escutcheon plate is then drawn tight against the wall, the packing 28 being compressed between the outer surface of the wall 23 and the portion 27 of the escutcheon plate. The portion 26 of the escutcheon plate projects into the opening within the wall from which the plaster ground 18 has been withdrawn. With the parts thus assembled, the handle knob may now be put in place. It comprises the gripping member or handle part 33 which, as shown at FIG. 8, is knurled at 34 and provided with a pointer 35. As shown in FIG. 12, the handle and supporting parts are assembled to permit the positioning of the handle as far inside the escutcheon as possible. Thus the tubular member 38 projects through the opening in the handle and its stop or stops 39 limit its movement in one direction by their contact with the portion 37. The handle cup as shown in FIG. 6 and FIG. 1 is put in place within the tubular member 38 and its movement in one direction is limited by its flange 43. The knob or handle is thus complete as shown in FIG. 12. A modification of this arrangement is shown in FIG. 10 in which the end of the stem 6 projects more nearly to the outer surface of the knob or handle 35. The structural details of this supporting means are described above and will not be repeated here.

With the handle complete in the form either of FIG. 10 or FIG. 1, the tubular portion 38 is slipped over the exposed end of the stem 6, the part 42, for example, of the tubular portion 38 being fitted over and engaging the flattened portion 47 of the stem 6. If desired there may be two flattened portions of the stem 6 and in that case the tubular member 38 would have two members or portions such as the portion 42. When the handle has been put fully into engagement with the stem, being moved in over the stem as far as the length of the flattened portion 47 permits, the screw 48 is then inserted in the tapped opening 49. It passes through the tubular portion 44 of the cup 43 and the flange of the screw rests upon the portion 45. When the screw has been screwed home, the handle is in complete location. The pointer 35 will generally be aligned with indicia on the escutcheon plate as indicated in FIG. 5 in which the letter H indicates the direction of handle movement for hot water and the letter C indicates the direction of handle movement for cold water.

When the handle is fully in place and the screw 48

has been drawn home, the finishing plate 50 is inserted in the outwardly directed cavity of the handle, the spring fingers 51 serving to hold it removably in place.

The method of assembly above described comprises, therefore, steps of locating and securing the housing member permanently in place in the water supply system and the steps of mounting upon the housing the plaster ground and causing it to remain in place until the plastering and other wall finishing are complete. During that time the stem and associated parts are protected by the cap 71. Further steps in the method include the removal of the cap 71 and the plaster ground when the plastering and other wall finishing are complete. Thereafter the escutcheon plate is mounted upon the housing and drawn into final position to close the opening left by the removal of the plaster ground and to furnish an ornamental finish for the exterior portion of the assembly. The escutcheon plate also serves to indicate the direction of handle movement to accomplish the proper water supply and water mixing. Further steps in the method include the assembly of the handle either as shown in FIG. 1 or in FIG. 10, the mounting of the handle upon the stem 6 and finally the finishing of the handle by the insertion of the finishing member 50.

In the rotation of the valve stem means are provided to act as a stop to limit the rotation in each direction. These means comprise the shoulders 53 and 53a and the portion 32 of the sleeve 31. In clockwise rotation the shoulder 53a contacts the member 32 and limits rotation in that direction. Correspondingly, in counter-clockwise rotation the shoulder 53 contacts the member 32 and limits rotation in that direction. By this construction and manner of operation the valve stem itself is protected from any strain or shock as a result of the stop movement. Since the handle stop mechanism is contained within the handle and the sleeve 31, there is no strain due to the stopping action upon the stem or the screw 60 which fastens the handle to the stem, and there is thus no tendency to loosen the handle on the stem nor to loosen the screw which fastens the handle to the stem.

In assembling the valve the extensions 5a on the housing 5, as shown particularly in FIGS. 2 and 4, serve as means to properly position the valve cartridge or valve assembly within the housing 5. As shown particularly in FIG. 2 members 6a of the valve cartridge or assembly are aligned with the extensions 5a of the valve housing 5. When the parts are in this position the valve assembly is properly positioned within the housing 5 and the plumber or other installer can be sure that he has mounted the valve assembly properly. The parts are then secured in proper position and alignment by a key 17 which extends through the keyways 16, as shown for example in FIGS. 2, 4 and 12.

I claim:

1. The method of installing a faucet, which includes the steps of fixing a housing in permanent position in relation to a support, securing a plaster ground member by securing parts upon said housing when so fixed, inserting a valve member in said housing, completing the plaster finishing of a wall adjacent said housing and against said plaster ground member on said housing, removing and discarding the plaster ground member, thereafter positioning within the cavity left by the removal of the ground member an escutcheon plate, securing said escutcheon plate by said securing parts in fixed relation to said housing, positioning a handle upon said valve member, and securing said handle to said valve member.

2. The method of installing a faucet, which includes the steps of fixing a housing in permanent position in relation to a support, securing a plaster ground member by securing parts upon said housing when so fixed, inserting a valve member in said housing, positioning a protective cap over the adjacent portion of said housing, completing the plaster finishing of a wall adjacent said

housing and against said plaster ground member on said housing, removing and discarding the plaster ground member and the protective cap, thereafter positioning within the cavity left by the removal of the ground member an escutcheon plate, securing said escutcheon plate by said securing parts in fixed relation upon said housing, positioning a handle upon said valve member, and securing said handle to said valve member.

3. The method of installing a faucet, which includes the steps of fixing a housing in permanent position in relation to a support, securing a plaster ground member by securing parts upon said housing when so fixed, inserting a valve member in said housing, completing the plaster finishing of a wall adjacent said housing and against said plaster ground member on said housing, removing and discarding the plaster ground member, thereafter positioning within the cavity left by the removal of the ground member an escutcheon plate, securing said escutcheon plate by said securing parts in fixed relation to said housing, positioning a handle upon said valve member, and securing said handle to said valve member.

4. The method of installing a faucet, which includes the steps of fixing a housing in permanent position in relation to a support, securing a plaster ground member by securing parts upon said housing when so fixed, inserting a valve member in said housing, separately positioning a separate protective cap over the adjacent portion of said housing, completing the plaster finishing of a wall adjacent said housing and against said plaster ground member on said housing, removing and discarding the plaster ground member and the protective cap, thereafter positioning within the cavity left by the removal of the ground member an escutcheon plate, securing said escutcheon plate by said securing parts in fixed relation upon said housing, positioning a handle upon said valve member, and securing said handle to said valve member.

5. The method of installing a faucet, which includes the steps of fixing a housing in permanent position in relation to a support, securing a plaster ground member by securing parts upon said housing when so fixed, inserting a valve member in said housing, completing the plaster finishing of a wall adjacent said housing and against said plaster ground member on said housing, removing and discarding the plaster ground member, thereafter positioning within the cavity left by the removal of the ground member an escutcheon plate, securing said escutcheon plate by said securing parts in fixed relation to said housing, positioning a handle upon said valve

10

45

member, and securing said handle to said valve member and applying a finishing plate to said handle.

6. The method of installing a faucet, which includes the steps of fixing a housing in permanent position in relation to a support, securing a plaster ground member by securing parts upon said housing when so fixed, inserting a valve member in said housing, completing the plaster finishing of a wall adjacent said housing and against said plaster ground member on said housing, removing and discarding the plaster ground member, thereafter positioning within the cavity left by the removal of the ground member an escutcheon plate, securing said escutcheon plate by said securing parts in fixed relation upon said housing, positioning a handle upon said valve member, and securing said handle to said valve member and applying a finishing plate to said handle.

7. The method of installing a faucet, which includes the steps of fixing a housing in permanent position in relation to a support, securing a plaster ground member by securing parts upon said housing when so fixed, inserting a valve member in said housing, separately positioning a separate protective cap over the adjacent portion of said housing which has received said valve, completing the plaster finishing of a wall adjacent said housing and against said plaster ground member on said housing, removing and discarding the plaster ground member and the protective cap, thereafter positioning within the cavity left by the removal of the ground member an escutcheon plate, securing said escutcheon plate by said securing parts in fixed relation upon said housing, positioning a handle upon said valve member, and securing said handle to said valve member and applying a finishing plate to said handle.
